Primary Examiner — John A Voytek(74) *Attorney, Agent, or Firm* — Peter A. Chiabotti;
Akerman LLP(57) **CLAIM**

The ornamental design for a tire as shown and described.

DESCRIPTION

FIG. 1 is a perspective view of my design;

FIG. 2 is a front view thereof; and,

FIG. 3 is a side view thereof.

The portions shown in broken lines form no part of the
claimed design.**1 Claim, 3 Drawing Sheets**(56) **References Cited**
